CLAIM

The ornamental design for a combined bucket lid, seat, and holder, as shown and described.

DESCRIPTION

FIG. 1 is a front-side perspective view of a combined bucket lid, seat, and holder, shown in an open position of use with an exemplary bucket, toilet paper, and towel.

FIG. 2 is a front-side perspective view thereof, shown in a closed position of use with an exemplary bucket, toilet paper, and towel.

FIG. 3 is a top plan view thereof.

FIG. 4 is a front-side elevation view thereof.

FIG. 5 is a back-side elevation view thereof; and,

FIG. 6 is a bottom plan view thereof.

The broken lines are shown for the purpose of illustrating environmental subject matter. None of the broken lines form part of the claimed design.
